[57] CLAIM

The ornamental design for a modular residential building, substantially as shown and described.

DESCRIPTION

FIG. 1 is a front elevational view of a modular residential building according to my invention;

FIG. 2 is a rear elevational view thereof;

FIG. 3 is a side elevational view thereof;

FIG. 4 is an elevational view of the side opposite that shown in FIG. 3;

FIG. 5 is a top plan view on a relatively reduced scale;

FIG. 6 is a front elevational view of a modified modular residential building according to my invention;

FIG. 7 is a rear elevational view of the building shown in FIG. 6;

FIG. 8 is a top plan view on a relatively reduced scale of the building shown in FIGS. 6 and 7;

FIG. 9 is a front elevational view of a second modified modular residential building according to my invention;

FIG. 10 is a rear elevational view of the building shown in FIG. 9;

FIG. 11 is a side elevational view of the building shown in FIGS. 9 and 10, and

FIG. 12 is a top plan view on a relatively reduced scale of the building shown in FIGS. 9, 10 & 11.

The sides of the modified modular residential building shown in FIGS. 6 and 7 are identical to those shown in FIGS. 3 and 4.

The side of the second modified modular residential building opposite that shown in FIG. 11 is identical to that shown in FIG. 3.

FIG. 1

FIG. 2

FIG. 5

FIG. 6

FIG. 7

FIG. 8

FIG. 9

FIG. 10

FIG. 11

FIG. 12
